UNITED STATES PATENT OFFICE.

GEORGE SOCHUREK, OF NEW YORK, N. Y.

TOY AIRPLANE.

1,323,112.

Specification of Letters Patent.

Patented Nov. 25, 1919.

Application filed February 5, 1919. Serial No. 275,067.

To all whom it may concern:

Be it known that I, GEORGE SOCHUREK, a citizen of the United States, and a resident of the city of New York, Astoria, borough 5 of Queens, in the county of Queens and State of New York, have invented a new and Improved Toy Airplane, of which the following is a full, clear, and exact description.

This invention relates to toys and has for 10 an object the provision of an improved construction which is adapted to be supported by a movable cable or support and arranged to move back and forth over the support, the arrangement being such that the toy 15 will turn as it reaches the end of its travel in either direction.

Another object of the invention is the provision of a flying toy in the nature of an airplane which is provided with a rudder and a controlling structure as a support, whereby the airplane will turn around each time it changes direction.

A further object of the invention is the provision of a toy airplane with a simple, 25 but strong arrangement of supporting struts and a set of removable stabilizing planes which hold themselves in position and at the same time hold the rudder in place.

In the accompanying drawing:

30 Figure 1 is a side view showing the toy embodying the invention as the same would appear in use.

Fig. 2 is a top plan view with certain parts broken away disclosing the same airplane illustrated in Fig. 1, the same being 85 on an enlarged scale.

Fig. 3 is an enlarged detail fragmentary sectional view through Fig. 2 on line 3—3.

Referring to the accompanying drawing 40 by numerals, 1 indicates a cable of any desired kind which may be secured to a hook 2 or other support, said cable being adapted to be handled by the hand of the operator at 3. This cable may be of any length and 45 it is designed to move the end 3 up and down as indicated by the dotted line, so that when the cable 1 is in the position shown in Fig. 1 the airplane 4 will move toward the hook 2, but when it is moved down to the 50 dotted position shown in Fig. 1 the airplane will turn around by reason of the tail 5 thereof acting against the air and will move toward end 3. The airplane 4 is preferably supported by a single cord 6 extending 55 through the upper plane 7 at the center of gravity of the airplane, said cord being divided at 8 so that there will be an individual cord at each side of the pulley 9, said individual cords being secured to the axle of shaft 10 extending through the pulley, said 60 pulley being, of course, grooved for straddling the cable 1.

The airplane 4 is provided with a fuselage 11 made from side members 12 and 13 which are preferably pasteboard, said side members being secured to block 14, which is preferably wood. Block 14 accommodates a pin 15 on which a propeller 16 is loosely mounted so as to be rotated by the air pressure as the fuselage moves through the air. 70 Coacting with upper plane 7 is a lower plane 17, said planes being connected by a plurality of front struts 18, and a plurality of rear struts 19. The struts 18 and 19 are flat and arranged at right angles to each other so 75 as to brace the planes 7 and 17 both longitudinally and transversely. Each of these struts is provided with a pair of spurs 20 and 21 at each end, said spurs extending through the respective planes or bent over 80 as shown in Fig. 2. Preferably the combined width of the two spurs 20 and 21 is less than the width of the struts whereby 85 shoulders 22 and 23 are provided against which the planes are pressed when the spurs 20 and 21 are bent over. At the rear of the fuselage the rudder 5 is provided with a 90 forwardly extending portion 24 which extends between the rear portions of the sides 12 and 13 and is clamped rigidly in place therebetween by the extensions 25 and 26 which project from the planes 27 and 28. The slot through the rear end of the respective side members 12 and 13 is just sufficiently large to allow the projections 25 and 95 26 to be squeezed therethrough whereby the parts are held in position by the friction, though if desired a little glue or other adhesive may be used. It will be noted that the rudder or tail 5 is at right angles to the 100 fuselage members 12 and 13 and therefore tends to keep the plane traveling in a straight away direction. When the cord is lowered, however, or moved in any direction, the plane will usually be tilted slightly, 105 or may be rotated on the suspending cord so that the tail or rudder will be tipped out of the perpendicular and a reaction between the air and the tail or rudder will cause a twisting action of the plane. This will result in 110

the airplane turning around so as to face in the direction of travel.

What I claim is:

1. A toy airplane comprising a fuselage, 5 lifting planes, a rudder, and a supporting member comprising a grooved wheel and a suspending cord connected to the airplane at its center of gravity, a cable acting as a track for said wheel whereby when the 10 cable is in one position the weight of the airplane and the action of the rudder will cause the airplane to move in one direction, and when the supporting member is tilted to the opposite position the weight will cause 15 the airplane to move in the opposite direction while the rudder will act on the air and turn the airplane so as to face in the direction in which it is traveling.

2. In a toy of the character described, an 20 airplane having a comparatively large rudder, a suspending cord connected with said airplane substantially at the center of balance, a grooved trolley wheel connected with said cord, and a supporting cable for said 25 wheel adapted to be connected to a fixed body at one end and held by the operator at the opposite end whereby as the operator raises and lowers the free end of the cord the weight of the pulley, airplane and associate 30 parts will cause the airplane to move from one end of the cord to the other, while the rudder acting on the air will turn the airplane so as to face in the direction in which it is traveling.

3. A toy airplane comprising a fuselage 35 formed from a block, a pair of side strips extending from the block rearwardly, the rear end of said strips being provided with apertures, a pair of lifting planes, struts for 40 connecting said lifting planes together, means for connecting one of the lifting planes with said block, a propeller mounted at the front of said fuselage, a rudder arranged at the rear of said fuselage with a 45 portion extending between said strips, and means extending through said apertures and said rudder for locking the rudder in place.

4. A toy airplane comprising a fuselage, steering and stabilizing means arranged at

the rear of the fuselage, a pair of lifting 50 planes, one of said lifting planes being connected with said fuselage, and a plurality of struts connecting said lifting planes, all of said struts being formed from flat material with one set of struts arranged so that the flat faces thereof will be parallel with 55 the front edge of the planes, and the other struts with the flat faces at right angles to the front edge of said planes, each of said struts having spurs extending therefrom 60 through the respective planes, said spurs being bent over so as to lock the planes to the struts.

5. A toy airplane comprising a fuselage, means at the rear for steering and stabilizing 65 the airplane, a pair of lifting planes arranged at the front of the fuselage, means for connecting one of said planes to the fuselage, and a plurality of struts for connecting the planes together, each of said 70 struts having a plurality of spurs at each end extending through the planes, said spurs being bent over for locking the planes to the struts.

6. A toy airplane comprising a fuselage 75 formed with a pair of side plates, a pair of lifting planes connected with the fuselage, a rudder connected with the rear end of the fuselage, and a pair of stabilizing planes arranged at the rear end of said fuselage 80 formed with projections extending through said plates.

7. A toy airplane comprising a fuselage having a pair of side plates, a pair of lifting planes connected to the fuselage near the 85 front, said side plates near the rear end being formed with registering apertures, a rudder having an apertured extension projecting between said side plates so that the aperture in the extension will register with 90 the apertures in the side plates, and a pair of stabilizing planes formed with projections constructed to extend through all of said apertures when in registry whereby the rudder is held in position and the stabilizing 95 planes are also held in position.

GEORGE SOCHUREK.
